ATTORNEY

UNITED STATES PATENT OFFICE

164,577

DISPLAY STAND

Raymond Lawton Henderson, Atlanta, Ga., assignor to Norris Inc., Atlanta, Ga.

Application May 11, 1951, Serial No. 15,137

Term of patent 7 years

(Cl. D80—9)

To all whom it may concern:

Be it known that I, Raymond Lawton Henderson, a citizen of the United States, residing at Atlanta, State of Georgia, have invented a new, original, and ornamental Design for a Display Stand, of which the following is a specification, reference being had to the accompanying drawing, forming a part hereof.

I claim:

The ornamental design for a display stand, as shown.

RAYMOND LAWTON HENDERSON.
